Des. 211,860
Patented Aug. 6, 1968

211,860

PULL

James R. Deadrick, Winston-Salem, N.C., assignor to
Stewart-Warner Corporation, Chicago, Ill., a corpora-
tion of Virginia

Filed Dec. 14, 1966, Ser. No. 5,032

Term of patent 14 years

(Cl. D10—8)

FIG. 1.

FIG. 2.

FIG. 3.

FIG. 4.

FIG. 1 is a top plan view of the pull incorporating the design;

FIG. 2 is a side elevational view of the pull incorporating the design;

FIG. 3 is a left end elevational view of the pull as seen in FIGS. 1 and 2; and

FIG. 4 is a right end elevational view of the pull as seen in FIGS. 1 and 2.

The dominant features of the design reside in the portions shown in full lines.

I claim:

The ornamental design for a pull, substantially as shown and described.
